UNITED STATES PATENT OFFICE.

HENRY MUELLER, OF DECATUR, ILLINOIS, ASSIGNOR TO H. MUELLER MANUFACTURING COMPANY, OF DECATUR, ILLINOIS, A CORPORATION OF ILLINOIS.

DESIGN FOR A PANTRY-COCK.

No. 39,792.

Specification for Design.

Patented Jan. 26, 1909.

Application filed February 18, 1907. Serial No. 358,118. Term of patent 14 years.

To all whom it may concern:

Be it known that I, HENRY MUELLER, a citizen of the United States, residing at Decatur, in the county of Macon, State of Illinois, have invented a new, original, and ornamental Design for Pantry-Cocks, of which the following is a specification, reference being had to the accompanying drawing, forming a part thereof.

Figures 1 and 2, are side and front elevations, respectively, and Fig. 3, a top plan, showing my new design for pantry cocks.

The salient and characteristic features of the design reside in the massive appearance of the structure produced by the gracefully curved lines, rounded corners, total absence of sharp angles, and the annular series of elliptical-shaped facets on the gland through

which the stem of the handle passes, said facets being separated one from the other by convex or outwardly curved walls that form continuations of the curved dome wall of the gland.

The absence of sharp angles, grooves and crevices renders the device highly sanitary as there are no places where foreign matter may collect or that can not be readily cleaned.

I claim:—

The ornamental design for a pantry cock as shown and described.

HENRY MUELLER.
